[57] ABSTRACT

A waveguide structure including at least one rotating joint between waveguides of circular cross-section is provided, on opposite sides of the joint, with groups of axially spaced elongate metallic elements which are arcuately curved in transverse planes of the circular waveguides and act as inductive differential phase shifters for microwaves to be transformed from linear to circular polarization or vice versa, the linearly polarized waves being fed in and taken off via adjoining waveguides of rectangular cross-section whose major surfaces include angles of 45° with chords spanning the arcuate elements. These elements may be divided into several groups spaced a quarter wavelength apart, with a larger separation between the elements within each group. They may also be alternately disposed at diametrically opposite locations in the circular waveguide.

ROTARY WAVE-GUIDE STRUCTURE INCLUDING POLARIZATION CONVERTERS

Certain kinds of microwave equipment, such as radar or therapeutic irradiation apparatus for example, incorporate a fixed section and a mobile section. It is then desirable to transmit the microwave energy from the fixed section, to the mobile section or vice-versa, through a waveguide which introduces no more than very minor disturbances in the transmitted signal.

The rotating element which is included in the transmission circuit conventionally employs dielectric fins arranged at the center of a circular waveguide, these fins having the well known properties of polarizing high frequency waves. However, these dielectric fins are fragile and, moreover, may develop breakdown phenomena whose magnitude depends upon the transmitted power and which always adversely affect the life time of the device. Added to these drawbacks is the difficulty of efficiently cooling these dielectric fins, which may reach very high temperatures.

It is an object of the invention to overcome these drawbacks.

A waveguide structure according to our invention, designed to convert linearly polarized (or plane-polarized) microwaves into circularly polarized microwaves and vice versa, comprises two waveguides of circular cross-section centered on a common axis, these circular waveguides being relatively rotatable about their axis by virtue of the interposition of a rotary joint enabling uninterrupted microwave transmission therebetween. An input waveguide of rectangular cross-section supplies the first circular waveguide with linearly polarized microwave energy having an electric field vector in a first radial plane including the waveguide axis; similarly, an output waveguide of rectangular cross-section extracts linearly polarized microwave energy from the second waveguide, the extracted energy having an electric field vector in a second radial plane including that axis. The first waveguide is provided with first inductive phase-shifting means comprising a first plurality of axially spaced elongate conductive elements of arcuate configuration connected at their ends to the inner peripheral surface of that waveguide and spaced therefrom between these ends while turning their concave sides toward the axis, a line spanning the ends of any element of this first plurality including an angle of substantially 45° with the aforementioned first radial plane. The second circular waveguide is provided with a second plurality of similar axially spaced arcuate elements whose ends are spanned by a line including an angle of substantially 45° with the second radial plane. In this way, a component of the electric field vector of an incoming linearly polarized wave is phase-shifted with reference to another component perpendicular thereto to provide circular polarization ahead of the rotary joint; analogously, beyond that joint, the circularly polarized wave is reconverted by a similar phase shift into a linearly polarized outgoing wave.

Instead of using incoming and outgoing rectangular waveguides centered on the axis of the rotary waveguides, we may replace each of these rectangular waveguides by a pair of perpendicular waveguides conveying respective energy components polarized in mutually orthogonal planes.

Furthermore, the rotary joint between the first and second circular waveguides could be replaced by a pair of axially spaced joints separated by a further waveguide of circular cross-section which may be provided with inductive phase-shifting means similar to those described above.

The above and other features of our invention will now be described in detail with reference to the accompanying drawing wherein:

FIG. 1 illustrates a conventional application of a rotating-joint waveguide structure;

FIG. 2 schematically illustrates a rotating-joint waveguide structure of conventional design;

FIGS. 3 and 4 respectively are a transverse section and a longitudinal view of a polarization transformer forming part of a waveguide structure in accordance with the invention;

FIG. 5 illustrates the relative positions of a rectangular-section waveguide and a circular-section waveguide electromagnetically coupled to one another, the electromagnetic wave propagating in the TE_{01} mode in the rectangular-section waveguide and in the TE_{11} mode in the circular-section waveguide;

FIG. 6 illustrates in detail a polarization transformer forming part of a waveguide structure in accordance with the invention;

FIG. 7 is a perspective view of a metal element included in the polarization transformer of FIG. 6;

FIG. 8 is a partial longitudinal section through another polarization transformer forming part of a waveguide structure in accordance with the invention;

FIGS. 9 and 10 are cross-sectional views respectively taken on the lines IX-IX and X-X of FIG. 8;

FIG. 11 is a longitudinal view of a waveguide structure in accordance with the invention;

FIG. 12 is a cross-sectional view taken on the line XII-XII of FIG. 11;

FIG. 13 illustrates another embodiment of a waveguide structure in accordance with the invention; and

FIG. 14 is a cross-sectional view of a modified polarization transformer coupled to two rectangular waveguides.

The waveguide structure shown in FIG. 1, of a type commonly used in radar antennas, for example, comprises a mechanical rotating joint 2 inserted between two polarization transformers 3 and 4 allowing and incident linearly polarized wave O_1 , issuing from a rectangular-section input waveguide 5, to be converted to a circularly polarized wave O_2 which is subsequently reconverted to a linearly polarized wave O_1 identical with the incident wave and transmitted to a rectangular-section output waveguide 6.

These polarization transformers 3 and 4 of conventional type have been shown in a more detailed fashion in FIG. 2. They respectively comprise high-frequency waveguides 8 and 9 having a circular cross-section; these waveguides 8 and 9 being the interposed mechanical rotating joint 2 (equipped with a microwave trap 7) enables the waveguide 9, for example, to rotate about the axis X_1X_2 while the waveguide 8 remains fixed. At the centers of the waveguides 8 and 9 there are respectively arranged dielectric fins 10 and 11 serving to introduce a differential phase shift. However, these dielectric fins 10 and 11 constitute discontinuities able to interfere with the proper operation and to shorten the life time of the rotating joint. In fact, because of the difference between the dielectric constant of the fins and

the dielectric constant of the air generally present within the waveguide, the electric field in this waveguide can develop high values in air, while being generally of reduced level in the dielectric fins. The difference in electric-field strengths gives rise to break down effects which can short-circuit the waveguide.

If, by way of example, we consider the case of a quartz fin introduced into the air-filled waveguide, then the electric-field-strength ratio in these two media is substantially 4:1, and this considerably limits the powers which can be used in a conventional rotating-joint structure, without any risk of breakdown.

These drawbacks are eliminated in accordance with our invention by a rotating-joint waveguide including modified polarization transformers. FIGS. 3 and 4 illustrate a transformer of this kind which comprises a circular-section waveguide 12 provided with a series of identical metal elements 13 each of which is located in a transverse plane of waveguide 12, as FIG. 3 shows. These metal elements 13 are produced from small metal bars of rectangular section, for example, with similar curvatures in their respective planes and with the major sides L of their cross-sectional rectangles extending in axial direction as shown in FIG. 7. The shape and position of these elements 13 in the circular-section waveguide 12, as shown in FIG. 5, are such that the curved faces of elements 13 are at right angles to the lines of force 14 of the electric field associated with the electromagnetic wave (TE₁₁ mode) transmitted through the circular-section waveguide 12.

These lines of force 14 are caused by a leading component of that wave, represented by a vector E_{NR}, whose lagging component is represented by a vector E_R. Elements 13 form inductive reactances effective to advance the phase of the lagging component E_R so that, when the two components are in phase, there results a vector E₁ parallel to the minor sides of an associated rectangular output waveguide 15 fed by the circular waveguide 12 as shown in FIG. 11. Thus, a line x₁-x₂ paralleling the major sides of that rectangle includes an angle of 45° with a chord a₁ - a₂ subtending the arc of elements 13 and with a line perpendicular thereto bisecting that arc. By the same token, a linearly polarized wave (TE₀₁ mode) arriving over the identical input waveguide 15 in FIG. 11 is differentially phase-shifted to become circularly polarized. Elements 13 turn their concave sides toward the axis of waveguide 12 and have their convex sides separated from its periphery by crescent-shaped spaces; thus, their radii of curvature are larger than the radius R of the waveguide. With this curvature, as seen in FIG. 5, the elements 13 intersect substantially perpendicularly the lines of force 14 associated with field vector E_{NR}.

The distance d separating the metal elements 13 from the center of the circular waveguide 12 (FIG. 3) is not critical but trials have led us to adopt a value of d > 2R/3 for this distance.

The metal elements 13, in the embodiments of FIGS. 4 and 11 are disposed parallel to one another, either in an equispaced relationship or, better still, in such a fashion as to form m groups of n elements each.

FIG. 6 illustrates an advantageous arrangement of the metal elements 13 forming two groups G₁, G₂ of two elements each. This arrangement facilitates the matching of the polarization transformer. Each of these groups represents an inductive obstacle producing a phase shift of $\pi/4$ and these two groups are separated

by a distance substantially equal to $\lambda g/4$, where λg represents the wavelength of the microwave transmitted through the waveguide 12. By way of example, if the frequency of the incident wave is 3,000 MHz (corresponding to a free-space wavelength $\lambda_0 = 10$ cm) and if the radius of curvature of the circular-section waveguide 12 is R = 4 cm, the wavelength λg in the circular waveguide 12 will be 14.70 cm and the distance between two groups G₁ and G₂ of obstacles will be $\lambda_g/4 = 3.67$ cm, the distance between two consecutive elements 13 in the same group being l = 4.6 cm.

The thickness e and the width L of the bars forming the metal elements 13 (FIG. 7) are chosen so that the admittance of the quadripole constituted by the polarization transformer including these elements 13 corresponds to suitable matching conditions.

Alternatively, we may provide in the circular-section waveguide 12 three groups of two elements each. In this case, the phase shift introduced by each group of elements will be substantially equal to $\Delta\phi = 30^\circ$.

Of course, these metal elements 13 can be also made with bars of circular section, the diameter of these bars then being determined in such a fashion as to achieve appropriate matching of the polarization transformer.

A rapid calculation shows the advantage of a polarization transformer in accordance with the invention as concerns the peak powers which can be transmitted. If E_M is the maximum electric field at the center of a circular waveguide, then the permissible peak power P_c is given by the relationship:

$$P_c = E_M^2 \cdot 2 \cdot 10^{-3} \cdot R^2 \cdot \frac{\lambda_0}{\lambda_g}$$

If R = 4 cm and E_M = 30 KV/cm (this value corresponding to the breakdown electric field in air), the peak power P_c is 19.5 MW at a frequency of 3,000 MHz.

Assuming that the strength of the electric field between the metal elements 13 is equal to 1.5 times the strength of the electric field in a circular waveguide, the permissible peak power P_t in the polarization transformer provided with these metal elements 13 is given by:

$$P_t = \frac{P_c}{1.5^2} = 8.7 \text{ MW}$$

The permissible peak power P_t in the polarization transformer can be increased by replacing the air usually present therein by, for example, sulphur hexafluoride.

Moreover, the metal elements 13 can readily be cooled and this makes it possible to operate the polarization transformer under very good conditions.

Also, it may be advantageous to arrange the metal elements 13 alternately at either side of a diametral plane of the circular-section waveguide 12, this plane being parallel to the delayed component E_R of the electric field E₁ of the plane-polarized wave.

However, the presence of the metal elements 13 in the circular-section waveguide 12, as well as the presence of mismatching at the junctions between circular and rectangular waveguides, gives rise to reflection phenomena producing parasitic modes in the rotating-joint structure in accordance with the invention. To

eliminate these parasitic modes, plates of resistive material (graphite, for example) can be arranged in the circular waveguide 12.

FIG. 11 illustrates a rotating-joint structure comprising two polarization transformers 18 and 19 separated by a rotary mechanism coupling 2. Each of these transformers 18 and 19, provided with metal elements 13, comprises a plate 20 of resistive material, respectively disposed at the input end 27 of the transformer 18 and at the output end 28 of the transformer 19, in a transverse plane, perpendicularly to the electric field E_1 of the normal TE_{01} propagation mode of the arriving microwave O_1 , the latter being linearly polarized (FIG. 12).

In some, it is desirable to be able to eliminate the phase shift introduced by the polarization transformers 18 and 12 between the incident and emergent linearly polarized waves, i.e., to reverse the sense of rotation of the electric-field vector of the circularly polarized wave between waveguides 18 and 19. In this case, a phase corrector 21 (FIG. 13), constituted by a circular waveguide 22 whose axis coincides with the axis Y_1Y_2 of the circular waveguide 12 and in which there are arranged metal elements 23 analogous to those of the polarization transformers 18 and 19, may be inserted between 20 the latter, these elements 23 being arranged in relation to one another in the waveguide 22 as to produce a phase shift of π in the phase corrector 21. In operation, the waveguide 22 will rotate about its axis at a velocity ω while the polarization transformer 19 will rotate about its axis with a velocity $\Omega = 2\omega$, the transformer 18 remaining fixed.

The rotary coupling between stages 18, 21 and 19 then comprise two mechanical joints 24 and 25, each of which being provided with a microwave trap, the phase corrector 21 being located between these two mechanical joints.

The rotating-joint waveguide structure thus obtained makes it possible to transmit large H.F. powers without producing a phase shift in the emergent wave.

In FIG. 14 we have illustrated the possibility of separately injecting the components E_R and E_{NR} of field vector E_1 (FIG. 5) of a circularly polarized wave into waveguide 12 with the aid of two conjugate rectangular waveguides 15a and 15b at the input end of the structure; an identical arrangement can be used, of course, for extracting these two components from such a waveguide 12 at the output end.

What we claim is:

1. In a waveguide structure for converting linearly polarized microwaves into circularly polarized microwaves and vice versa, in combination:

a first and a second waveguide of circular cross-section centered on a common axis;

joint means between said first and second waveguides

enabling relative rotation thereof about said axis with uninterrupted microwave transmission therebetween;

input waveguide means of rectangular cross-section connected to said first waveguide for supplying same with linearly polarized microwave energy having an electric field vector in a first radial plane including said axis;

output waveguide means of rectangular cross-section connected to said second waveguide for extracting therefrom linearly polarized microwave energy having an electric field vector in a second radial plane including said axis;

first inductive phase-shifting means in said first waveguide comprising a first plurality of axially spaced elongate conductive elements of arcuate configuration connected at their ends to the inner peripheral surface of said first waveguide and spaced therefrom between said ends thereof while turning their concave sides toward said axis, a line spanning the ends of any element of said first plurality including an angle of substantially 45° with said first radial plane; and

second inductive phase-shifting means in said second waveguide comprising a second plurality of axially spaced elongate conductive elements of arcuate configuration connected at their ends to the inner peripheral surface of said second waveguide and spaced therefrom between said ends thereof while turning their concave sides toward said axis, a line spanning the ends of any element of said second plurality including an angle of substantially 45° with the said second radial plane.

2. The combination defined in claim 1 wherein the elements of each plurality are parallel to one another.

3. The combination defined in claim 1 wherein the elements of each plurality are alternately disposed at 30 diametrically opposite locations of the respective waveguide.

4. The combination defined in claim 1 wherein the elements of each plurality are divided into several groups spaced apart by substantially a quarter wavelength at the frequency of said microwave energy, the spacing of the elements within each group being greater than said quarter wavelength.

5. The combination defined in claim 4 wherein the relative phase shift introduced by the elements of each 40 group between energy components polarized in said first and second planes and energy components polarized perpendicularly thereto is substantially 90° .

6. The combination defined in claim 1 wherein at least one of said waveguide means of rectangular cross-section comprises a pair of rectangular-section waveguides conveying respectively energy components polarized in mutually orthogonal planes.

7. The combination defined in claim 1 wherein said first and second waveguides are provided with respective conductor plates lying in diametrical planes perpendicular to said first and second radial planes, respectively.

8. The combination defined in claim 1 wherein said elements are flat bars with major faces parallel to said axis.

9. The combination defined in claim 1 wherein said joint means comprises a pair of rotary joints separated by a further waveguide of circular cross-section.

10. The combination defined in claim 9 wherein said further waveguide is provided with further inductive phase-shifting means substantially identical with said first and second phase-shifting means.
